CLAIM

The ornamental design for a cockpit center console, as shown and described.

DESCRIPTION

FIG. 1 is a front perspective view of a cockpit center console showing our new design;

FIG. 2 is a front view thereof;

FIG. 3 is a first side view thereof;

FIG. 4 is a second side view thereof; and,

FIG. 5 is a top view thereof, the bottom view forming no part of the claimed design.

The broken lines illustrate structure and environment that form no part of the claimed design.
